(57) **CLAIM**

The ornamental design for a standard handset escutcheon, as shown and described.

DESCRIPTION

FIG. 1 is a perspective view of the handset escutcheon. FIG. 2 is top view of the handset escutcheon.

FIG. 3 is a bottom view of the handset escutcheon.

FIG. 4 is a front view of the handset escutcheon; and, FIG. 5 is a side view of the handset escutcheon.

The broken line showing of the environment is for illustrative purposes only and forms no part of the claimed design. The side view opposite FIG. 5 is a mirror image of FIG. 5 and is not shown.
